(57) **CLAIM**

The ornamental design for a high bay light fixture, as shown and described.

DESCRIPTION

FIG. 1 is a front, downward perspective view of a high bay light fixture;

FIG. 2 is a front, upward perspective view thereof;

FIG. 3 is a front elevational view thereof, the rear elevational view being identical thereto;

FIG. 4 is a right side elevational view thereof, the left side elevational view being a mirror image thereof;

FIG. 5 is a bottom plan view thereof; and,

FIG. 6 is a top plan view thereof.

The broken lines represent elements which form no part of the claimed design.
